(Continued)

Primary Examiner — Jennifer L Watkins*Assistant Examiner* — John Patrick G Ribay**CLAIM**

(57) The ornamental design for the insole, as shown and described.

DESCRIPTION

FIG. 1 is a top perspective view of an insole design showing my new design.

FIG. 2 is a front view of the insole.

FIG. 3 is a rear view of the insole.

FIG. 4 is a left view of the insole.

FIG. 5 is a right view of the insole.

FIG. 6 is a top view of the insole.

FIG. 7 is a bottom view of the insole.

FIG. 8 is a bottom perspective view of the insole.

FIG. 9 is an enlarged view of FIG. 6; and,

FIG. 10 is an enlarged view of FIG. 7.

The broken lines in FIGS. 6, 7, 9, and 10 depict the cut line of the enlarged views and from no part of the claim.
